CLAIM

The ornamental design for a pop-up card holder, as shown and described.

DESCRIPTION

FIG. 1 is an isometric view of a pop-up card holder in a fully open position;

FIG. 2 is a front elevation view thereof;

FIG. 3 is a back elevation view thereof;

FIG. 4 is a left elevation view thereof;

FIG. 5 is a top plan view thereof;

FIG. 6 is a bottom plan view thereof;

FIG. 7 is a front perspective view of the closable card holder in a partially closed position;

FIG. 8 is left elevation view thereof;

FIG. 9 is a top plan view thereof; and,

FIG. 10 is a bottom plan view thereof.

The phantom and/or broken lines are for illustrative purposes only and form no part of the claimed design.
